WITNESS:

H. C. Fratt,
INVENTOR
BY Victor J. Evans

ATTORNEY

UNITED STATES PATENT OFFICE.

HARRY C. FRATT, OF NORRISTOWN, PENNSYLVANIA.

REFRIGERATOR LINING.

Application filed February 13, 1925. Serial No. 9,052.

To all whom it may concern:

Be it known that I, HARRY C. FRATT, a citizen of the United States, residing at Norristown, in the county of Montgomery and State of Pennsylvania, have invented new and useful Improvements in Refrigerator Linings, of which the following is a specification.

My invention is a refrigerator lining and its primary object is to provide a lining for refrigerators which is so constructed and arranged as to eliminate grooves or corners for the accumulation of food products or other foreign matter which would tend to render the refrigerator unsanitary.

A further object of the invention is to provide a refrigerator lining which permits the partition and shelf or ice supporting pan to be removed so that the interior of the refrigerator may be kept in a sanitary condition at all times.

With the preceding and other objects and advantages in mind, the invention consists in the novel combination of elements, construction and arrangement of parts and operations, to be hereinafter specifically referred to, claimed and illustrated in the accompanying drawings, wherein:

Figure 1 is a vertical sectional view of the refrigerator embodying my improvement.

Figure 2 is a horizontal sectional view taken on line 2—2 of Figure 1, and

Figure 3 is a fragmentary sectional view taken on line 3—3 of Figure 2.

Referring to the drawings in detail wherein corresponding characters of reference denote corresponding parts throughout the several views, the numeral 5 designates a refrigerator of a conventional character having the usual door 6 at the front thereof.

The invention contemplates a novel lining which may be galvanized iron or suitable non-corrosive metal. This lining is indicated at 19 and is substantially rectangular and open at the front thereof. The outer edge of the lining is formed with a marginal flange 11 which engages over the edges of the refrigerator frame, shown in Figure 1. As clearly shown in Figure 2, the lining is arranged in spaced relation to the sides, and rear wall of the refrigerator to provide a dead air space therebetween which serves to retain the cool air in the refrigerator and prevent the ingress of heat.

The lining 19 is provided with a central longitudinal channel or groove 12 which receives a double walled partition 13. The forward edge of this partition is accommodated in a recessed face 14 of one of the frame elements of the refrigerator.

The invention also contemplates a removable metallic ice supporting pan 15 having a marginal flange 16 and further provided with a pair of spaced bosses or tongues 17 which is received in channels or grooves 17' formed in the rear wall of the lining 19. The forward edge of this pan rests in a recessed face 14 of one of the frame members of the refrigerator. It will be observed that in order to move the ice supporting pan it is only necessary to lift the forward edge from the recessed face of the frame member and slide the pan forwardly through one of the door openings.

A drip tube 18 leads from the rear end of this pan for the purpose of conducting drippings therefrom.

From the disclosure it will be apparent that I have provided a simple and inexpensive lining for refrigerators which is constructed from one piece so that crevices and grooves will be eliminated which usually render the refrigerator unsanitary. Also the partition and ice supporting pan may be removed at will for the purpose of cleaning the same and the lining proper.

While I have shown and described the preferred embodiment of the invention, I desire to have it understood that such changes may be made in the form, construction, arrangement of parts and operations as will not depart from the spirit of the invention or the scope of the subjoined claims.

What is claimed is:

1. The combination with a refrigerator, of a metallic casing arranged therein and spaced from the walls of the refrigerator and provided with groove and a plurality of sockets in its rear wall, a partition arranged within the casing and having one edge received in the groove and an ice supporting pan provided with projections on its rear edge which are received in the sockets.

2. The combination with a refrigerator including a non-metal casing, a metallic casing arranged therein and open at the front and having a marginal flange which over-

lies the outer edge of part of the refrigerator casing, the metallic casing being provided with sockets in its rear wall, a partition arranged vertically in the metallic casing and a refrigerator pan arranged horizontally in the metallic casing and having a marginal flange, projections formed on the

marginal flange and received in the sockets in the metallic casing, and a supporting element upon which the forward edge of the pan rests.

In testimony whereof I affix my signature.

HARRY C. FRATT.
